UNITED STATES PATENT OFFICE.

FREMONT F. WHITMORE, OF SEATTLE, WASHINGTON.

BOLTING-UP DEVICE.

1,340,470.

Specification of Letters Patent. Patented May 18, 1920.

Application filed March 6, 1919, Serial No. 281,011. Renewed April 7, 1920. Serial No. 372,096.

To all whom it may concern:

Be it known that I, FREMONT F. WHITMORE, a citizen of the United States, and resident of the city of Seattle, county of 5 King, and State of Washington, have invented certain new and useful Improvements in Bolting-Up Devices, of which the following is a specification.

My invention relates to new and useful 10 improvements in bolting-up devices and more particularly to that class of bolt-up devices as employed by "bolter-ups" in the ship building construction. The present system of securing together ship 15 plates, boiler plates and plates of like character, preliminary to riveting, entails gangs of two men each, a bolter-up and a helper, the helper is employed to insert the bolts through the holes in the plates and 20 holds the head thereof between a wrench; or other suitable tool, to preclude the rotation of the bolt when the bolter-up on the opposite side of the plate is applying the nut thereto.

25 The object of this invention is to provide a bolt of novel design that will eliminate the services of the helper to the bolter-up. A further object resides in the simplicity of construction of a bolt having a headless end 30 that is adapted to be inserted through the holes of two or more superimposed plates and having means provided on its headless end that is adapted to be automatically projected laterally after the bolt has been inserted through the holes so as preclude its 35 withdrawal.

Other objects will appear from a study 40 of the following specification, illustrated in the accompanying drawings, and finally pointed out in the appended claims.

In the drawings,

Figure 1 is a view in side elevation of a bolting-up device.

Fig. 2 is a plan view of the same, and,

45 Fig. 3 is a view in side elevation, showing it applied to the plates preparatory to urging them together.

Referring more particularly to the drawings, in which like reference numerals indicate like parts, the numeral 4 represents 50 a bolt having a stem which is threaded in the usual manner. The outer end of this stem is preferably flattened, as at 5, on two sides, and can be provided with a hole 6, 55 through the center, for the reception of a drift pin (not shown); or the flattened sur-

face can be engaged by a wrench and the bolt held against rotation when the nut 15 is applied thereto. The headless end of the bolt is preferably tapered so as to be more 60 easily inserted through the holes 7 of the plates 8.

Upon opposite sides of the headless end of the bolt, in reversed relation, are provided angular-shaped slots 9, and pivotally disposed within each of these respective slots, is a pin 10, of similar size and shape, to conform to the angular contour of the slots when disposed in their normally closed position, as shown in Fig. 1.

70 When these pins are extended laterally, as shown in Fig. 3, the elongated ends 11 thereof project outwardly at right angles with respect to the bolt, and the shoulders 12 thereof are in abutment with the correspondingly shaped shoulders 13 of the slot. A bearing is likewise formed on the shoulders 14 of the slot and the peripheral outer edge of the pins' elongated ends, which 75 serves to impart rigidity against displacement when in this extended position.

The operation of this bolt tightening device is obvious. The headless end is first inserted through the holes in the superimposed plates 8 until the headless end is extended sufficiently past the outer side thereof to give clearance for the elongated end of the pin to swing downward by gravity until it assumes the position as shown in Fig. 3, precluding the bolt's withdrawal through 80 the holes. The nut 15 can then be screwed up tightly and the respective plates 8 will be urged together.

In the event the bolt should turn freely when the nut is applied thereto, a drift pin 95 held by one hand, can be inserted through the hole 6, or a wrench applied to the flattened part 5 thereof, and with the bolter-up's other hand free the nut 15 can be screwed down tightly, thus eliminating the 100 services of the helper on the opposite side of the plate.

While I have shown two pivotally attached members to the bolt, it is to be understood that one or more will suffice.

105 Having thus described my invention, what I claim as new and desire protected by Letters Patent, is:

1. A bolting up device comprising a bolt having one end threaded to receive a nut, 110 the other end of the bolt having recesses in its sides consisting of a transversely ex-

tending part and a part extending length-wise of the bolt and having a side wall at one side, and bars pivoted in the transversely extending part of said grooves 5 and each having an end adapted to fit within the longitudinally extending part of one of the grooves, said bars having side surfaces adapted to engage the side walls of the transversely extending part of the 10 grooves when the bar is placed in a transverse direction.

2. A bolting-up device for tightening plates together comprising a member threaded at one end thereof and adapted to be

held against rotation on its threaded end, 15 a nut carried by said threaded end, the unthreaded end of said member adapted to be inserted through the holes in said plates, angularly shaped slots provided on opposite sides of said unthreaded end, pins pivotally 20 disposed within said slots having shoulders adapted to abut against the shoulders of said slots when swung to a lateral position, whereupon said plates can be urged together when said nut is screwed down tightly. 25

Signed at Seattle, Washington, this 27th day of February, 1919.

FREMONT F. WHITMORE.
